Primary Examiner — Anhdao Doan(74) *Attorney, Agent, or Firm* — DLA Piper LLP (US)(57) **CLAIM**

We claim the ornamental design for a monolayer, as shown and described.

DESCRIPTION

FIG. 1 is a front perspective view of a monolayer showing our new design;

FIG. 2 is a top plan view thereof;

FIG. 3 is a bottom plan view thereof;

FIG. 4 is a right elevational view thereof;

FIG. 5 is a left elevational view thereof;

FIG. 6 is a rear elevational view thereof; and,

FIG. 7 is a front elevational view thereof.

The broken lines illustrate portions of the monolayer that form no part of the claimed design.
